portion pivotally secured as at 25 to the upper portion of the closure plate 23, also on a horizontal axis, but downwardly spaced from the pivot axis 22. The lower end portion of the link 24 is bifurcated as at 26 to receive between the forks 27 thereof the reduced neck 15 of the crank pin 14, see particularly Figs. 2 and 3. The extreme free ends of the fork 27 are brought into close engagement with each other as indicated at 28 to confine the crank pin 14 therein while permitting rotary movements of the link 24 with respect thereto.

From the above, it should be obvious that rotation of the knob 5 imparts through the link 24 swinging movements of the closure plate 23 toward and from a relatively closed position with respect to the perforations 3 in the register plate 1. However, under certain conditions, it is frequently found desirable and necessary to shift the range of swinging movements of the closure plate 23, whereby to cause same to open still further than shown in Fig. 2 while obviously not closing as completely as would result from the adjustment indicated in Fig. 2. This may be brought about by merely loosening the stop screw 20 with respect to the lock nut-acting washer 10. Thereafter, the adjustment plate 6 is rotated about the shaft 4 by manually grasping the pointer 7, the stop screw 20 moving within the slot 21 in the register plate the desired extent. Thereafter, of course, the stop screw 20 is again brought into clamping engagement with the washer 10.

My invention has been thoroughly tested and found to be completely satisfactory for the accomplishment of the above objects, and while I have shown a preferred embodiment thereof, it should be obvious that same is capable of modification without departure from the scope and spirit of the appended claims.

What I claim is:

1. In a device of the class described, a perforate register plate, a closure plate for said register plate, means pivotally mounting one side of said closure plate rearwardly of said register plate for swinging movements toward and away from a closed position relative to said register plate, means for imparting said swinging movements to said closure plate, said means comprising a rotary shaft journaled in said register plate, a disc-like member fast on ally connected to said crank pin and said closure plate and having a crank pin projecting rearwardly therefrom in

5 offset parallel relationship to said shaft, a rigid link pivotally connected to said crank pin and said closure plate and movable by said crank pin during rotation of said shaft in opposite directions to impart said swinging movements to said closure plate, said disc-like member being notched to define circumferentially spaced abutment portions, a stop element operatively carried by said register plate and projecting rearwardly therefrom into said slot and engageable with said abutment portions upon rotation of said shaft in opposite directions to positively limit rotary movements of said shaft in opposite directions, an operating knob on said shaft forwardly of said register plate, and means for varying the range of opening and closing swinging movements of said closure plate with respect to said register plate, said means comprising an adjustment plate loosely rotatably mounted on said shaft intermediate said knob and said register plate, and a clamping washer encompassing said shaft intermediate said closure plate and said disc-like member, said register plate having a segmental slot therein concentric with said shaft and in alignment with the notch in said disc-like member, said stop element being in the nature of a clamping screw projecting loosely through said adjustment plate and extending slidably through the segmental slot in said register plate and into the notch in said disc-like member, said clamping screw having a head engageable with said adjustment plate and having screw threaded engagement with said clamping washer.

2. The structure defined in claim 1 in which said crank pin defines a reduced neck, one end of said rigid link being bifurcated to receive said neck, the free ends of the fork defined by the bifurcated end portion of said link being in substantial engagement with each other whereby to permit rotation of said crank pin relative to said link but preventing longitudinal displacement of said link with respect to said crank pin.
